UNITED STATES PATENT OFFICE.

ALONZO E. RHOADES, OF HOPEDALE, MASSACHUSETTS, ASSIGNOR TO DRAPER CORPORATION, OF HOPEDALE, MASSACHUSETTS, A CORPORATION OF MAINE.

FILLING-END-RETAINING MEANS FOR WEFT-REPLENISHING LOOMS.

1,285,386.

Specification of Letters Patent. Patented Nov. 19, 1918.

Application filed March 6, 1918. Serial No. 220,682.

To all whom it may concern:

Be it known that I, ALONZO E. RHOADES, a citizen of the United States, residing at Hopedale, county of Worcester, State of Massachusetts, have invented an Improvement in Filling-End-Retaining Means for Weft-Replenishing Looms, of which the following description, in connection with the accompanying drawing, is a specification, like characters on the drawing representing like parts.

This invention relates to weft replenishing looms particularly of the automatic type and its object is to provide means for catching and thus retaining the trailing end of the abandoned filling carrier after it is discharged from the shuttle in the operation of replenishment so that it will not be caught and carried by the shuttle or the fresh filling carrier into the cloth upon the succeeding pick. This object is secured in the present invention by providing means for clamping the trailing end against the usual chute which guides the filling carrier in its discharge and holding the end clamped until it is withdrawn from the shuttle by the flight of the shuttle.

These and other objects of the invention will appear more fully from the accompanying description and drawings and will be particularly pointed out in the claims.

In the drawings,

Figure 1 is a view in front elevation of a sufficient portion to disclose the invention of the replenishing end of the well known Northrop automatic filling replenishing loom together with a preferred form of the invention embodied therein;

Fig. 2 is a view in end elevation partially in cross section of the construction shown in Fig. 1.

The present invention is not concerned with the particular construction or operation of the general features of the loom to which it is applied. For convenience of illustration the invention is shown, in the preferred form selected, as embodied in an automatic weft replenishing loom of the well known Northrop type.

In this type of loom the frame or loom side 1 supports at the replenishing or transfer end of the loom a hopper stand 2 upon which is mounted a rotary hopper 3 carrying a supply of fresh filling carriers 4. The lay 5 carries at the transfer end the shuttle

box 6 and the lay and shuttle box are provided with a vertical opening 7 therethrough to permit the downward discharge of the abandoned filling carrier when the shuttle is boxed at the transfer end of the loom. 60

A transferrer 8 is pivotally mounted on the hopper stand on a stud or shaft 9 projecting laterally therefrom. Upon the call for filling replenishment the usual controller shaft or starter rod 10 extending across the front of the loom is rocked and through mechanism not necessary here to describe or illustrate, because well known and familiar to those skilled in the art, the transferrer 8 is swung downwardly to force a fresh filling 70 carrier, in this case a bobbin, from the hopper 3 into the shuttle 11 then boxed at the transfer end of the loom and thereby to discharge the abandoned or exhausted filling carrier or bobbin in the shuttle down 75 through the opening 7.

The end of the filling extending from the abandoned filling carrier through the eye of the shuttle is usually, in feeler looms, severed by suitable mechanism adjacent the 80 nose of the shuttle and this severed end must be drawn back and out through the eye of the shuttle and clear of the shuttle or it is liable to be caught by the shuttle or by the fresh filling carrier and dragged back 85 into the shed and woven into the cloth thus causing an imperfection.

This invention provides a simple and effective means to catch and retain this filling end when the filling carrier is discharged 90 from the shuttle and prevent it from being dragged back into the shed by the shuttle or by the fresh filling carrier.

The abandoned filling carrier in its discharge is usually guided downwardly into a receiver, such as a box placed beneath the loom, by a metal plate forming a chute. Such a chute 12 is shown mounted on a rod 13 projecting laterally from a bracket 14 secured to the loom side 1. This chute is inclined rearwardly and when the lay beats up to bring the shuttle box beneath the hopper the upper edge of the chute will be at the rearward edge of the opening 7 so that as the discharged filling carrier falls it will 105 be guided by this inclined chute into the receiver.

In this invention means are provided which, immediately after the discharge of the abandoned filling carrier, act to clamp 110

the end trailing from the abandoned filling carrier against the face of the chute so that as the shuttle takes its flight the trailing end is pulled out through the eye of the shuttle 5 and clear the shuttle.

A preferred form of mechanism for accomplishing this end is illustrated in the drawings. A movable clamping member herein shown as an arm 15 is pivotally mounted 10 on the shaft 13 and extends upwardly and is bent laterally and rearwardly to present a portion 16 parallel with the upper edge of the chute 12. Preferably this portion 16 of the clamping member is provided 15 with some suitable means for enabling it efficiently to clamp or pinch the filling and for that purpose a strip of leather 17 is shown as set into the portion 16. Preferably also the face of the chute 12 coöperating with the 20 clamping edge of the clamping member is grooved at 18 so that when the clamping action takes place the leather strip 17 swings into the groove 18.

The clamping member is provided with 25 means which normally act to move it into clamping engagement with the chute. For this purpose the arm 15 of the clamping member is shown as journaled on the rod 13 between two collars 19 and 20. The collar 30 19 is recessed and in this recess is mounted a helical spring 21 one end of which is secured to the collar 19 and the other to the arm 15. A set screw 22 enables the tension of this spring to be adjusted by a rotary adjustment 35 of the collar 19. Means are provided to hold the clamping member withdrawn from the chute. For this purpose a hook shaped latch 23 is secured to a rod 25 journaled in a laterally extending hub 26 formed on an 40 arm 27 conveniently mounted on an extended portion of the transerrer shaft 9. This rod 25 carries at its opposite end adjustably secured thereto a depending tail 28. The hub 26 is recessed and in this recess is 45 mounted a helical spring 29 one end of which is secured to the hub and the opposite end to the latch 23, and this spring acts normally to depress the latch. The clamping member 15 at its upper edge opposite the 50 latch is provided with a catch 30 coöperating with the latch. Hence when the clamping member 15 is swung forwardly the latch 23 rides over the catch 30 and holds the clamping member in forward position as 55 shown in Fig. 2.

The clamping member 15 is swung forwardly into engagement with the latch through means operated by the lay and thus the clamping member is moved away from 60 the chute prior to the discharge of the filling carrier upon the beat up of the lay to bring the shuttle beneath the hopper when replenishment is to take place. For this purpose the clamping member 15 is preferably provided with a bunter 31 projecting rear-

wardly therefrom and preferably made in two parts and longitudinally adjustable by means of the clamping screw 32. This bunter extends into the path of the lay so as to be struck thereby upon the beat up.

During the normal operation of the loom the clamping member is held in its forward position by the latch 23 with the bunter out of contact with the lay so that there is no operation of the clamping member. When, however, weft replenishment is to take place means are provided for releasing the latch.

The latch releasing means are preferably operated by or through the weft replenishing mechanism upon the call for weft replenishment or prior to weft replenishment taking place. This may conveniently be done by the construction illustrated in which an arm 33 is adjustably mounted on the end of the controller shaft or starter rod 10 and projects rearwardly beneath the tail 28 of the latch.

The downward movement of the latch 23 may be limited by an abutment 34 thereon contacting with a stop 35 on the arm 27.

The operation of the mechanism will now be apparent. The parts during the normal operation of the loom are in the position indicated in Fig. 2. When the filling in the running shuttle has become substantially exhausted and weft replenishment is to take place the starter rod 10 is rocked through the operation of any of the well known mechanisms provided for that purpose. This operation raises the arm 33 which strikes the tail 28 and raises and holds the latch 23 elevated thus releasing the clamping member 15 which at once swings rearwardly into clamping engagement with the chute 12, bringing the clamping member into the position shown in dotted lines in Fig. 2. The lay 5 now beats up to bring the shuttle into position beneath the transerrer. As the lay beats up it strikes the bunter 31 swinging the clamping member forwardly, the operation of transfer takes place during which the fresh filling carrier is pushed into the shuttle and in turn pushes the substantially exhausted filling carrier down through the opening 7 and the abandoned filling carrier falls down the chute 12 and behind the clamping member now in its forward position leaving its end trailing from the shuttle eye down over the face of the chute. The lay now starts on its rearward movement and as it does so the clamping member swings rearwardly and comes into clamping engagement with the chute thus pinching or clamping the end trailing from the abandoned filling carrier between the edge, in this case, the leather strip 17 of the clamping member, and the chute, in this case the groove 18, of the chute. The shuttle now takes its flight and as it does so the trailing end of the abandoned filling carrier being held pinched

by the clamping member and the chute is drawn out through the eye of the shuttle and thus all danger of the trailing end being caught by the shuttle or by the fresh filling carrier and carried or thrown back into the shed is removed.

Upon the next succeeding beat up of the lay the arm 33 has dropped to its lower position and the lay striking the bunter 31 will 10 swing the clamping member 15 forwardly until it is caught by the latch. Hence the clamping member will again resume and remain in its locked position until replenishment is again to take place.

Having fully described my invention, what I claim as new and desire to secure by Letters Patent is:

1. In a weft replenishing loom, a lay provided with a shuttle box and having an 20 opening therethrough to permit the discharge of the abandoned filling carrier, a chute mounted on the loom frame and acting to guide the filling carrier in its discharge, a movable clamping member coöperating with the chute, and means acting to cause the said clamping member to clamp the filling end, extending from the filling carrier discharged down said chute, against the chute and to hold said end until withdrawn from the shuttle by its flight.

2. In a weft replenishing loom the construction defined in claim 1 in which the chute is provided with a groove and the clamping member with an edge fitting in 35 the said groove when the clamping action takes place.

3. In a weft replenishing loom the construction defined in claim 1 in which the chute is provided with a groove and the clamping member with a strip of leather fitting into said groove when the clamping 40 action takes place.

4. In a weft replenishing loom the construction defined in claim 1 together with 45 means for preventing the operation of the clamping member during the normal operation of the loom.

5. In a weft replenishing loom, a lay provided with a shuttle box and having an 50 opening therethrough to permit the discharge of the abandoned filling carrier, a

chute mounted on the loom frame and acting to guide the filling carrier in its discharge, a clamping member, means acting normally to move said clamping member 55 into clamping engagement with said chute, means to hold said clamping member withdrawn from said chute, means operated by or through the weft replenishing mechanism to release said holding means prior to weft 60 replenishment taking place, and means operated by the lay to move the said clamping member away from the chute prior to the discharge of the filling carrier, whereby upon the backward movement of the lay 65 the clamping member moves into engagement with the chute clamping the filling end extending from the discharged filling carrier and causing said end to be withdrawn 70 from the shuttle in its flight.

6. In a weft replenishing loom, a lay provided with a shuttle box and having an opening therethrough to permit the discharge of the abandoned filling carrier, a chute mounted on the loom frame and acting to guide the filling carrier in its discharge, a clamping member, means acting normally to move said clamping member 75 into clamping engagement with said chute, a pivotally mounted latch acting to swing 80 into engagement with and hold said clamping member withdrawn from said chute, means operated by or through the weft replenishing mechanism to release said latch prior to weft replenishment taking place, 85 and maintain said latch released during weft replenishment, and a bunter projecting from said clamping member into the path of the lay whereby upon the beat up of the lay prior to replenishment the clamping 90 member is moved and held away from the chute during the discharge of the abandoned filling carrier and whereby upon the succeeding backward movement of the lay the clamping member moves into engagement 95 with the chute clamping the filling end extending from the discharged filling carrier and causing said end to be withdrawn from the shuttle in its flight.

In testimony whereof, I have signed my 100 name to this specification.

ALONZO E. RHOADES.
